Primary Examiner—Adir Aronovich*(74) Attorney, Agent, or Firm*—Baker Botts LLP(57) **CLAIM**

The ornamental design for a maraca, as shown and described.

DESCRIPTION

FIG. 1 is a front elevational view of a maraca showing my new design;

FIG. 2 is a top plan view thereof;

FIG. 3 is a bottom plan view thereof; and,

FIG. 4 is a right side elevational view thereof.

The undisclosed rear and left side elevational views are mirror images of the front and the right side elevational views respectively.
